CURTAIN TYPE INSIDE STORM WINDOW PROTECTION

Carl V. Bergstrom, Milwaukee, Wis.

Application February 6, 1950, Serial No. 142,699

3 Claims. (Cl. 160—40)

1

The invention relates to curtains and more particularly to a curtain arranged and constructed to function as an inside storm window.

Usually storm or winter protection for window openings is provided by an exterior storm window or specially constructed double pane windows. One object of this invention is to provide an inexpensive storm protection for windows in the form of a curtain readily mounted adjacent the inner side of the window to act as a storm sash and also provide for light transmission and permit of ready adjustment for ventilation.

A further object of the invention is to provide an inside storm window protection particularly suited for use in connection with metal casement windows to eliminate the excessive condensation usually occurring in cold weather when metal windows are used.

A further object is to provide a combination inside storm protection and decorative mesh curtain.

Another object of the invention is to provide an inside curtain type storm protection for windows which can be left up permanently through all seasons of the year without affecting insulating efficiency, translucency, or desired summer ventilation.

A further object of the invention is to provide novel methods or means for quickly mounting the curtain rod or rods between the jamb faces of the window frame.

The invention further consists in the several features hereinafter described and more particularly pointed out in the appended claims.

In the drawings:

Fig. 1 is an inside elevation view of a curtain type storm window protection embodying the invention;

Fig. 2 is a detailed vertical sectional view taken on the line 2—2 of Fig. 1;

Fig. 3 is a detailed horizontal sectional view taken on the line 3—3 of Fig. 1;

Fig. 4 is an elevational view of a curtain rod, parts being broken away;

Fig. 5 is a view similar to Fig. 4 showing another curtain rod;

Fig. 6 is a view similar to Fig. 4 showing another form of curtain rod;

Fig. 7 is a view similar to Fig. 4 showing another form of curtain rod;

Fig. 8 is a detailed enlarged vertical sectional view taken on the line 8—8 of Fig. 1;

Fig. 9 is a vertical sectional view through a window curtain embodying the invention, parts being broken away;

2

Fig. 10 is a detailed sectional view showing certain modifications.

Referring to the drawings, the numeral 10 designates the permanent window frame provided with the usual sash opening in which the window 11 is mounted. As shown, the window 11 has a metal sash frame 12 having a glass light or pane 13.

10 Mounted within the frame 10 and in spaced relation with the inner side of the window 11 so as to provide a dead air space 14 is a curtain 15 embodying the invention arranged and constructed to function as an inside storm window.

15 The curtain 15 is preferably formed of two curtain sections, each carried at the top by a supporting rail 16 and held in position at the bottom by a rail 17.

20 Each of the curtain sections are of thin, flexible or pliable translucent or transparent plastic sheeting formed in two layers 18 joined together adjacent their top and bottom edges by stitching or other suitable fastening means 19 and spaced apart inwardly of their joined portions to provide a dead air space 20. The curtain sections are of 25 a width so that they overlap each other in the closed position of the curtain and also closely engage the sides of the window frame 10 where parts thereof adjacent said sides may be gathered. The layers of each curtain section are of a length so that their end headings or portions 21 may diverge from each other, as most clearly shown in Fig. 9, and have brushing contact with the upper and lower portions of the window frame 10, so that the curtain in closed position forms an effective barrier for the passage of any air past the sill, jambs, and header of the window frame 10 that may seep through the window 11 and provides the dead air space 20 between it and the window 11.

40 The layers 18 of the curtain are kept permanently separated by the rails 16 and 17 which engage the upper and lower joined edges of said layers, said rails being of a width to provide the desired dead air space 20 between the layers.

45 The upper supporting rail 16 is formed of telescoped metal bars 22 so that they may be readily adjusted to different widths of window openings. In Fig. 4 the bars 22 are formed of channel sections while in Figs. 6 and 7 the bars 50 are tubular sections. For firmly mounting the rail in the window frame 10 I have shown in Fig. 4 each of the bars 22 as having pointed prongs 23 extending from the channel web and also an apertured ear 24 extending from this 55 web to receive a screw or nail 25. In Fig. 6

each tubular bar has an end plug 24a provided with a spiked end 25a. In Fig. 7 the outer end of each bar carries a rubber plug 26 provided with a suction cup. The rail structures above described may also be used as bottom rails 17 or the structure shown in Fig. 5 may be used for this purpose. Referring to Fig. 5, the rail is formed of channel shaped telescopically fitted metal bars 27 which have weights 28 mounted in their ends, Fig. 9 showing an end view of one of these bars.

In using the spiked end rails, the operator first telescopes the bars of the rail so that it may be placed inside the window opening and then brings it into the desired horizontal position within said opening and then pushes the bars apart so that their spiked ends will engage the side jambs of the window and thus prick marks the place of attachment of the rail. He then removes the rail and separates the bars from each other and then each bar of the rail is separately hammered into the jamb at the prick guide points. Then the spiked ends are pulled out of the enlarged holes and the telescoping sections are again put together and the rail threaded through the curtain and then the rail with the curtain thereon is again placed in position and the bars extended so that the spiked ends engage in the holes in the jamb formed as above described. When the rails are of the form shown in Fig. 4 after the above procedure has been followed, the nails or screws 25 are inserted in the ears 24 and firmly fastened in the jamb.

As noted above, the rail forms shown in Figs. 4, 6, and 7 may be used at the top and also at the bottom. Where the weighted rail shown in Fig. 5 is used at the bottom, it is only necessary to thread this through the layers forming the curtain to hold the curtain suspended from the top rail and bring the diverging ends of the layers forming the lower heading into brushing contact with the window sill.

The curtain sections as noted are of thin, flexible or pliable translucent or transparent plastic sheeting and this sheeting may be decorated with designs formed in or on the sheeting so that the curtain acts as a decoration as well as an insulator. In packaging the curtain for merchandising no attempt would be made to provide exact sewed lengths for all windows but preferably only the top edge would be sewed and the bottom edge would be cut to fitting length by the purchaser and sewed or stapled together adjacent the bottom to accommodate the lower rail which may be placed about one inch above the sill. The curtains would also be of several widths, and the extra width material would be bunched, folded, or gathered adjacent either jamb effectively providing seals between the curtain and the sides of the window frame.

The curtain sections overlap along the central portion of the window for sealing purposes and for ventilating purposes this overlap can be opened up by spreading the sections apart along either of the rails but preferably above the lower rail to provide periodic winter ventilation and both sections parted or folded back toward either side along their rails for more complete summer ventilation. Fig. 1 shows in dotted lines the lower portions of the curtain sections parted for winter ventilation. The curtain sheeting must be sufficiently tough and pliable so that it may be repeatedly gathered or folded without developing cracks or wrinkles.

If a further seal at the sill of the window is

desired, I have shown in Figs. 2 and 8 a strip 29 of felt or other suitable material mounted on angled brackets 30 attached to the sill adjacent the lower edge of the curtain.

It is to be noted that the curtain, when hung, should be tensioned between the upper and lower rails; this being effected either by the weighted lower rail or the proper spacing of the upper and lower fixed rails. Normally for winter use the central portion of the curtain, when closed, should be kept free of folds to provide for better light transmission and viewing if transparent. From the above it will be noted that I have provided a curtain disposed adjacent the usual window to provide a dead air space between the curtain and the window and in which the curtain itself is formed of spaced layers of material which form a dead air space acting as an inside storm window which due to the formation of the curtain may be partially or fully opened or shut from the inside as desired.

Instead of using the felt strip 29 as shown in Fig. 8, felt strips 31 may be mounted at the top and bottom portions of the window so as to be overlapped by the diverging ends of the curtain as indicated in Fig. 9 and act as a supplemental barrier for the passage of cold air past the curtain.

It will also be noted that certain advantages of the invention may be obtained if the dead air space in the curtain itself is omitted but the curtain otherwise constructed so as to be hung within a window with the diverging ends formed by folded portions of the curtain above and below the hangers brushing the top and bottom portions of the window, as shown in Fig. 10. In other words, such a curtain has a single sheet of material forming the complete curtain whether such material is of single or laminated structure.

I desire it to be understood that this invention is not to be limited to any particular form or arrangement of parts except in so far as such limitations may be included in the claims.

What I claim as my invention is:

45. 1. An inside storm protection for windows comprising a curtain formed of widthwise separable sections, each section formed of multiple layers of translucent flexible plastic sheeting, means joining the layers of each section together adjacent their top and bottom edges, said sections being of a width so that they overlap each other in the closed position of the curtain and so that the outer side edge of each section engages the adjacent side of the window, and rails at the upper and lower portions of said curtain engageable with said joined portions to spread said layers apart between said joined portions to provide a dead air space and tension said layers between said joined portions, the upper of said rails having means for attaching it to the sides of a window opening.

2. An inside storm protection for windows comprising a curtain formed of widthwise separable sections, each section formed of multiple layers of translucent flexible plastic sheeting, means joining the layers of each section together adjacent their top and bottom edges and providing diverging complementary header sealing flap portions having brushing contact with the adjacent side of the window opening, said sections being of a width so that they overlap each other in the closed position of the curtain and so that the outer side edge of each section engages the adjacent side of the window, and rails at the upper and lower portions of said curtain engageable

with said joined portions to spread said layers apart between said joined portions to provide a dead air space and tension said layers between said joined portions, the upper of said rails having means for attaching it to the sides of a window opening.

3. The structure as defined in claim 2 in combination with barriers of flexible material mounted on and extending lengthwise of the top and bottom of the window opening and in engagement with and disposed between said complementary header sealing flap portions.

CARL V. BERGSTROM.
